CHRISTOPHER W. SKOW, OF NEWTON, IOWA

DISK SUPPORTING AND FEEDING MECHANISM FOR DISK SHARPENERS

Application filed February 2, 1931. Serial No. 512,901.

The object of this invention is to provide, in that type of disk sharpeners employing a pair of coacting rolls for drawing out the periphery of the disk to a thin edge for sharpening the same, improved means for holding and grinding the disk being sharpened in proper operative relation with said rolls, whereby the feeding action of the disk may be stabilized and steadied to more accurately form the sharpened edge than has heretofore been possible, especially when the periphery of the disk has been nicked or unevenly worn.

More specifically it is the object of this invention to provide an improved mechanism for operating and controlling the disk holding means whereby the feeding suction of the disk may be easily and quickly increased or decreased at the will of the operator.

This invention consists in the construction, arrangement and combination of the various parts of the device, whereby the objects contemplated are attained, as herein-after more fully set forth, pointed out in my claims, and illustrated in the accompanying drawings, in which:

Figure 1 is an end elevation of a disk sharpener showing the manner in which my improved holder is attached thereto.

Figure 2 is a sectional view on the line 2-2 of Figure 1.

Figure 3 is a side elevation of the disk holder showing diagrammatically the manner in which the disk may be tilted relative to the pressure rolls of the sharpener.

Figure 4 is a detail sectional view taken on the line 4-4 of Figure 1.

Figure 5 is a diagrammatical view showing the disk in solid lines in one position relative to the pressure rolls, and by dotted lines the normal position.

Figure 6 is a detail sectional view taken on the line 6-6 of Figure 2.

In the accompanying drawings the reference numeral 10 indicates base blocks designed to support the legs 11 of the frame 12. Said frame 12 is provided with upwardly extending supports 13. Said supports 13 are provided with bearing blocks

14 in which are rotatively mounted roller shafts 15 and 16, said shafts being rotated in opposite directions by means of suitable gear mechanism 17 of ordinary construction.

Pressure is applied to the top shaft 16 by means of a screw threaded shaft 18 operated by means of a lever 19. On the forward end of the shaft 16 is a roller 20, and on the forward end of the shaft 15 is a roller 21, said rollers being slightly tapered in the manner illustrated in Figure 1.

The shafts 15 and 16 are mounted in a common vertical plane. Supported in the lower end of the forward member 13 is a block 22 in which is rotatably mounted a stub shaft 23 having its rear end provided with a washer 24 and a nut 25 for securing said washer to the rear end of the shaft 23. The forward end of the shaft 23 is provided with an enlarged portion 26. The members 24 and 26 provide means for preventing sliding movement of the shaft 23 in the block 22.

The forward end of the member 26 terminates in a block 27, said block being designed to pivotally and slidably receive one end of a guide bar 28. Said guide bar 28 is provided with a guide 29, having a laterally extending portion 30 in which is rotatively mounted a shaft 31 terminating in a head portion 32, designed to support the central portion of a disk 33. The said disk 33 is secured in position by means of a bolt 34 and washers 35. The shaft 31 is supported in front of the end of the shaft 16 and substantially in a common plane.

The parts 30, 31, 34 and 35 constitute what I shall term a disk clamp.

Secured to the outer end of the bar 28 is a block 36 having a downwardly extending portion 37 for receiving a screw threaded shaft 38. The inner end of the shaft 38 is rotatively mounted in a downwardly extending portion 39 from the guide 29. A crank 40 is secured to the outer end of the shaft 38.

Rotation of the shaft 38 will cause the guide block 29 to move longitudinally of the bar 28 to accommodate disks of various diameters, in such a manner that the periph-

ery of the disk may be fed between the rollers 20 and 21 in the manner clearly illustrated in Figure 1.

The block 36 is supported by means of a fork 41 in which is mounted a screw threaded shaft 42, having a turn-buckle 43 in its lower end. Said turn-buckle is mounted on a shaft 44, the lower end of which is provided with a block 45. The block 45 is supported by links 46 having their upper ends pivotally connected with the block 27.

By this arrangement it will be seen that rotation of the turn-buckle 43 will cause the outer end of the guide bar 28 to be elevated or lowered, and the inclination of the shaft 31 varied relative to the axis of the shaft 15 to accommodate disks of various curvatures.

It will also be seen that the block 45 is free to swing laterally about the center of the shaft 23, causing the upper end of the shaft 31 to be tilted laterally and relative to the common plane of the shafts 15 and 16, in such a manner as to swing the center of the disk to a position laterally to one side of the common plane of the shafts 15 and 16, as illustrated by solid lines in Figure 5, and thereby change the relative feeding angle of the periphery of the disk relative to the periphery of the pressure rollers, in such manner that if the upper end of the shaft 31 is swung laterally in one direction, the tendency to feed the disk radially into the rollers will be increased, while if the upper end of the shaft 31 is rotated in the opposite direction, the tendency to feed the periphery of the disk radially to position between the rollers will be decreased.

If the shaft 31 is tilted laterally to position in a common plane, then the tendency of the disk to be drawn into position between the pressure rolls or propelled therefrom will be substantially zero.

If the shaft 31 is tilted laterally in such a manner as to cause the disk to be fed into the rollers, then it will be seen that a strain is placed on the shaft 31 tending to bend its upper end inwardly, causing the shaft 31 to operate firmly against its bearings, and thereby prevent any chattering or loosening in the movement of the disk, as the rollers 20 and 21 are rotated.

It will further be seen that a certain radial drawing action of the metal of the disk will also be encountered, which increases the tendency toward drawing the periphery of the disk to a thin edge, and increasing the speed of the sharpening action.

By placing the disk under an inwardly feeding strain, it will readily be seen that the beveled portion formed by the rollers 20 and 21 will be absolutely concentric to the center of the disk, inasmuch as the shaft is firmly supported in its bearings against inward and outward movement, so that the finished edge of the disk will be perfectly

concentric with its center. This inward drawing action of the rollers is of particular advantage when sharpening disks having notched peripheries, as the disk is firmly held against inward and outward movement at the time the notch of the periphery passes between the rollers, which would result if the disk were fed between the rollers with no drawing action.

To accomplish the lateral swinging movement of the block 45, I have provided the following mechanism:

Pivottally secured to the upper surface of the rear one of the blocks 10 is a bracket 47 to which is pivotally connected a link 48, by means of a rivet 49. The forward end of the link 48 is pivotally connected to a rearwardly extending portion 50 of the block 45, by means of a pivot 51. The link 48 prevents forward and rearward movement of the block 45, and yet permits lateral swinging movement about the center of the shaft 23.

Secured to one of the links 46 is a brace member 52, having its upper end connected to a lever 53. One end of the lever 53 is secured to the block 27. The lever 53 provides means whereby the lateral swinging movement of the block 45 may be manually controlled, which in turn controls the lateral tilting movement of the shaft 31, above referred to.

By this arrangement it will readily be seen that the inward drawing action of the disk may be increased or decreased by elevating or lowering the free end of the lever 53, thereby providing means whereby the drawing action of the rollers on the periphery of the disk is always under the control of the operator to meet the required conditions.

I claim as my invention:

1. In a disk sharpener, the combination of a support, a pair of coacting pressure rolls, a rotatively mounted disk clamp having its axis substantially perpendicular to the axes of said rolls and substantially in a common plane therewith, a frame for supporting said disk clamp, means for pivoting said frame about an axis parallel with the axes of said rolls, said frame including a downwardly extending portion, a horizontal link pivoted to the downwardly extending portion of said frame, means for pivoting one end of said link, and a laterally extending handle for said pivoted frame.

2. In a disk sharpener, the combination of a support, a pair of coacting pressure rolls, a rotatively mounted disk clamp having its axis substantially in a common plane with the axes of said rolls, a frame for supporting said disk clamp, means for pivoting said frame about an axis parallel with the axes of said rolls, said frame having a downwardly extending portion, a horizon-

tally arranged link having one end pivotally connected to the lower end of said downwardly extending portion and its opposite end pivotally connected to said support, and a handle for swinging said frame about its pivotal axis, substantially as and for the purposes stated.

3. In a disk sharpener, the combination of a support, a pair of coacting pressure rolls, a rotatively mounted disk clamp having its axis substantially perpendicular to the axes of said rolls and substantially in a common plane therewith, a frame for supporting said disk clamp, means for pivoting said frame to permit the frame to swing in a plane perpendicular to the axes of said rolls, and a handle for swinging said frame about its pivotal axis, substantially as and for the purposes stated.

20 CHRISTOPHER W. SKOW.
